United States Patent Office

DAVID MATTHEW, OF PRAIRIE DU CHIEN, WISCONSIN.

Letters Patent No. 65,759, dated June 11, 1867.

IMPROVEMENT IN FERRULES FOR TUBULAR BOILERS.

The Schedule referred to in these Letters Patent and making part of the same.

Be it known that I, DAVID MATTHEW, of Prairie du Chien, Crawford county, State of Wisconsin, have invented a new and improved Ferrule or Flue-Mouth and Ring, which prevents the rapid burning out and destruction of the flue ends and sheet in tubular or flue-boilers, and promotes a better combustion and entrance of the combustible gases into the flues; and I do hereby declare that the following is a full, clear, and exact description thereof, reference being had to the accompanying drawings, and to the figures and letters, in which like letters indicate similar parts.

Figure 1 is a vertical section on the line a' a' of fig. 2, showing the flue-sheet A, and end of flues C, and ferrule or flue-mouth B, and ring D, underneath the ferrule B, to accelerate the gases, compress and consume them as they enter the flues, and to retain luminous or other products between the outer surfaces of the ferrules, the ring D, and the flue-sheet A, to prevent the burning up of the flue-sheet.

Figure 2 is a front view of the enlarged or trumpet-mouths of the ferrules B, and part of the flue-sheet A and ring D under the ferrules, with bolt e to secure it to the flue-sheet.

The nature of my invention consists in making the ferrules used to support the ends of the flues in the furnace end in the flue-sheet in the form of a bell, trumpet, or funnel-shape, enlarging, and so that the large open end B shall protrude out into the furnace, say, one inch, more or less, beyond the flue or tube-sheet, with their large ends coming in contact with each other, or nearly so, having the entrance or mouth made bell, trumpet, or funnel-shaped, of larger area than that of the flue, with their small ends fitted to the flues, as is the common ferrule. The large end extending into the furnace becomes highly heated, and the products of combustion or smoke and gases coming in contact with these highly-heated enlarged ends, with their tapering mouths, become accelerated and concentrated or compressed, and ignite and consume the combustible gases, and produce a volume of flame into the tubes or flues, which combustible gases or matter would not otherwise be ignited, but would be condensed and deposited in soot by coming in contact with the colder surfaces of the flue-sheet and flues or tubes, they being at a much less degree of heat than the bell-mouths of the ferrules in the furnace or fire. Also, in applying a projecting ring or flange, D, under or around the lower or outer series of ferrules, to form a support or enclosure to the ashes and other matter which are deposited between the ferrules against the flue-sheet and protect it from burning out.

I construct my bell-mouth ferrules B of good Scotch or other soft iron, that will stand a strong heat and not crack or fly with fire. The boilers are constructed in any of the usual forms of tubular or flue-boilers, where the flames and heat pass through the flues or tubes, but in order to avoid the rapid destruction of the flue or tube-ends and sheet and the waste or escape of the ignitable gases, as is common in the tubular or flue-boiler, I make a bell-mouth ferrule, B, say of two inches length, with the small end turned to fit the flue C, after it has been put in and mandrelled out to the tube or flue-sheet A, and to the taper of the mandrel used to expand the tube or flue, the small end entering and is driven into the tube or flue one inch, more or less, as is common, while the large end will project out from the tube or flue one inch, (see fig. 1.) B B are the ferrules, A is the flue-sheet, and C C the flues. The enlarged mouths of the ferrules coming together, or nearly so, forming a complete screen for the flue-sheet, and the spaces or cavities between the bell-mouth ends and the flue-sheet fill up with luminous ashes, or other products of combustion, while the surface thus exposed to the volume of smoke and gases is at a very high heat, where it is accelerated and compressed or concentrated by the bell-mouths of the ferrules into the flues or tubes, burning up, and passes off more rapidly, giving off its volume of heat to the flues or tubes, making the flue surface more effective, while the large ends of the ferrules form a perfect screen for the flue-sheet and tube or flue ends, with the cavities filled up with a non-conducting material for its protection, supported and held in place around them by the ring D.

What I claim as my invention, and desire to secure by Letters Patent, is—

1. The projecting ferrules B, constructed and arranged as and for the purpose herein set forth.
2. I claim the ring D combined with the projecting ferrules in front of the flue-sheet to protect it as set forth.

DAVID MATTHEW.
